CLAIM

The ornamental design for a horse shoe, as shown and described.

DESCRIPTION

FIG. 1 is a bottom perspective view of a horse shoe showing my new design;

FIG. 2 is a front view thereof;

FIG. 3 is a right-side view, the left-side view being a mirror image thereof;

FIG. 4 is a back view thereof;

FIG. 5 is a top view thereof;

FIG. 6 is a bottom view thereof; and,

FIG. 7 is a top perspective view.

The broken lines showing a tire tread pattern in FIGS. 1-4, 6, 7 depict portions of the horse shoe that form no part of the claimed design.

1 Claim, 5 Drawing Sheets
